UNITED STATES PATENT OFFICE.

GEORGE B. WADSWORTH, OF COVINGTON, KENTUCKY, ASSIGNEE TO THE WADSWORTH ELECTRIC MANUFACTURING COMPANY, OF COVINGTON, KENTUCKY, A CORPORATION OF KENTUCKY.

FUSE-MOUNTING DEVICE

1,402,128.

specification or Letters Patent. Patented Jan. 3, 1922.

Application filed August 14, 1916. Serial No. 114701.

To all whom it may concern:

Be it known that I, GEORGE B. WADSWORTH, a citizen of the United States, and a resident of the city of Covington, in the county of Kenton and State of Kentucky, have invented certain new and useful Improvements in Fuse-Mounting Devices, of which the following is a full, clear, and exact description, reference being had to the accompanying drawings, forming part of this specification.

My invention relates to devices for electric installation which are used for mounting the fuses. In the usual construction, there is a switch of the desired number of poles, mounted on a suitable wall plate or in a suitable box, with the fuses secured in the box or on the plate. The wires are brought in from the service mains and secured first to the fuses, and then led to the switch. Thus the fuses are always connected to live wires, and as long as there is any access to the fuses there is the likelihood of the theft of electric current, as well as the chance of completing a circuit across the fuses by the hand or body and getting a shock.

It is impractical, in preventing the theft of current, to provide a box which locks up the fuses, as this will require the calling in of an officer with a key whenever it becomes necessary to change fuses. Without some means of protecting the switch from chance contact with some article lying across the poles and short circuiting the current across the switch, it is not proper practice to run service wires direct to the switch.

In a former application dated August 9th, 1916, I have described a device for electric installation, in which the service wires are led first to a switch and thence to the fuses, in which device the switch is sealed up and operated by a handle which extends out of its compartment, and the fuses are accessible without opening up the switch compartment.

It is the object in the invention in the present application to provide a device whereby the current may be led first to the fuses and thence to the switch, and in which the fuse holders are movable but not removable. Thus the object is to provide a fuse holder which will be movable so that the fuse proper will be accessible, and which movement will disconnect the fuse holder

from the live service wires, but in which the holder cannot be removed from the box so as to permit the theft of current from the service wires where they are joined to the fuse holders.

In the drawings,

Figure 1 is a perspective view of the casing for holding the switch and fuse connections.

Figure 2 is a vertical section of the same.

Figure 3 is a horizontal section taken through the fuse holders, and showing these parts in plan.

Figure 4 is a front elevation with the cover of the casing removed.

The fuse holders and the switches are mounted in a box or casing, preferably rectangular in the rear portion 1, of shape and provided with a front portion 2 seated within the flanged rim 3 of the casing and adapted to be locked or sealed thereto in any suitable way.

Secured to the rear wall of the casing and projecting outwardly therefrom is a rectangular block 4, provided with sockets to receive the slideable fuse holders 5 and 6. These fuse holders are provided with metallic clips 7 and 8 to receive the fuses 9, one for each of the two in and out connections. The fuse holders are made up of suitable non-conducting material and the spring clip 7 is in connection with the metallic connecting piece 10, which is bifurcated to engage the projecting contact plate 12 on the base of the box through which connection is made with one of the binding posts 13 and 14 of the two service wires 15 and 16. Connection is also made from the spring-pressed plunger 18 in the base of the binding post 19. This post 19 is connected by the wire 20 with the switch contacting piece 21 and through the pivoted switch closing bar 22 to the binding post 23 and thence to the house connection.

The switch and fuse box illustrated is for a two wire service, and the bar 24 corresponding to the bar 22, makes a connection with the switch contact piece 25, wire 26 and thence through the other fuse to the service line.

Of course it will be understood that as many wires may be employed with their accompanying fuses and switches as desired,

but the two wire service sufficiently illustrates the construction, the two parts being in duplicate. The switch is opened or shut by turning the handle 27, mounted on the rock shaft 28, journaled in suitable supports 29, 29, on the block 4. The rock shaft 28 carries the arm 30 connected by the link 31 with the lug 32 on the switch plate, and the shaft 28 also carries a segment piece 33 bearing the words "On" and "Off", which are visible through the window 34 in the casing, so as to show whether the switch is open or closed. The fuse holders 5 and 6 project through an opening 35 in the front of the lid 2 of the casing, so that they are always accessible and are provided with the handles 36, 36, so that the fuse holders can be drawn outwardly to expose the fuses when it is desired to change them. Each fuse holder is provided with a projection 37 which engages behind a shoulder 38 at the outer portion of the block 4, so as to prevent the fuse holders being entirely withdrawn from the box. With this construction, it will be evident that when the fuse holder is drawn out to insert a new fuse, the wire connection will be broken. As the fuse holder is drawn out, the plate 10 is disconnected from the contact piece 12 and the plunger 18 from the plate 17. The fuses are entirely inaccessible until the fuse holders are drawn out, so that there is no danger whatever of inserting or removing the fuse, even if the current is on. The service wires can therefore be connected directly to the fuses, but to obtain access to the fuses, the live wire connection must be broken. The switch connections are also covered up and protected so that there is no opportunity for short-circuiting the current across the switch through any chance contact, and while the fuse holders can be drawn out to obtain access to the fuses, the holders cannot be removed from the box to permit any improper connection with the service wires.

Having thus described my invention, what I claim as new and desire to secure by Letters Patent, is:—

1. In combination with a closed casing in which are placed fuse terminals, switch terminals and a switch, means for movably mounting a fuse to slide it into and out of connection with the fuse terminals, said means being irremovable from the casing, and adapted to take a position to expose the fuse, without exposing the fuse terminals or the switch.

2. In a switch box, a casing, a switch concealed therein, with an operating handle outside the casing, fuse terminals, switch terminals and connections, concealed therein, and movable fuse-holders therein, adapted when moved into one position to place fuses into the electric connections between the fuse terminals ahead of the switch, and when moved to another position to break the electrical connection ahead of the switch and expose fuses held thereon, without exposing the switch or the fuse terminal.

3. Means for mounting a fuse, comprising a casing, a member movable but irremovable from the casing, fuse terminals in the casing, said movable member being adapted to contact with the terminals in one position and to conceal the terminals in all positions, and a switch in the casing, with operating handle outside the casing, said movable member also adapted to conceal the switch in all positions.

4. In a switch box, a chamber, a fuse holder sliding in the chamber and adapted to close the chamber in all positions, against access to any terminals, a switch therein, with operating handle outside the chamber, electric terminals in the chamber, and a space in the holder to receive a fuse, said holder being adapted to contact with the terminal when the fuse space therein is concealed within the chamber.

GEORGE B. WADSWORTH.
